UNITED STATES PATENT OFFICE.

NEWTON E. WILLIAMS, OF NEW BRITAIN, CONNECTICUT.

CANOPY-TOP FOR BOATS.

1,202,255.

Specification of Letters Patent.

Patented Oct. 24, 1916.

Application filed April 23, 1915. Serial No. 23,474.

To all whom it may concern:

Be it known that I, NEWTON E. WILLIAMS, a citizen of the United States, residing at New Britain, in the county of Hartford, 5 State of Connecticut, have invented certain new and useful Improvements in Canopy-Tops for Boats; and I do hereby declare the following to be a full, clear, and exact description of the invention, such as will 10 enable others skilled in the art to which it appertains to make and use the same.

This invention relates to improvements in awnings and particularly to awnings for open boats.

15 The principal object of the invention is to provide an awning for an open boat, such as a small motor boat, which can be easily handled to be raised and lowered by one man.

Other objects reside in the peculiar construction and arrangement of the parts 20 whereby this result is accomplished.

In the drawings: Figure 1 is a side elevation of my invention applied to a small boat and in elevated position, Fig. 2 is an end elevation, of a fragment of the device, Fig. 3 is a top plan view of one end of the device, the awning cover being broken away, Fig. 4 is an enlarged section on the line 4—4 of Fig. 3, Fig. 5 is an enlarged transverse section on the line 5—5 of Fig. 3, and Fig. 6 is an enlarged vertical longitudinal section through the central portion of the ridge pole.

Referring particularly to the accompanying drawing, 10—10 represents a pair of upright posts secured respectively in the fore and after parts of the cock pit of the boat. These uprights are formed with a plurality of openings 11, the purpose of which will appear later.

40 Mounted to slide vertically on each of the uprights is a sleeve 12, on one side of which is integrally formed an extension 13 having the oppositely directed bracket arms 14. In the upper part of the extension 13 is a notch 45 15 in which notch are received the inner apertured ends of the internally threaded sleeves 16. A bolt 17 is passed through the extension 13 and apertured ends of the members 16 whereby said members are pivotally connected to said extension. On the outer

face of the extension is a pair of apertured lugs 18 between which are received the lugs 19 of a screw cap 20. A pivot pin 21 is passed through these lugs, as clearly shown.

Slidably disposed through the extension 55 13 is a spring-pressed bolt 21', the inner end of which engages in any one of the openings 11 while the outer end is provided with an eye 22 receiving the hooked end 23 of a rod 24. Screwed into the cap 20 is a hollow rod 60 25, there being one for each of the devices mounted on the standards, these rods 25 meeting at a central point between the uprights and connected together by a threaded sleeve 26. The adjacent ends of the rods 25 65 have openings 27 in their lower sides through which extend finger pieces 28 which are connected to the adjacent ends of the rods 24 before-mentioned. It will thus be seen that by drawing the finger pieces 28 toward each other that the rods 24 will pull the bolts 21 within the extensions 13 so that the sleeve 12 can be readily slipped up or down on the uprights.

Screwed into the sleeves 16 are rods 29, 75 these rods extending laterally of the bolt as clearly shown, in the rear elevation. Secured over the rods 25, which together form the rigid pole of the awning top and over the laterally extending rods 29 is a canvas 80 or other water-proof fabric 30. By means of the pivotal connections of the members 16, either pair on the same side of the uprights can be swung upwardly and over to rest on the other similar members, as desired. 85

What is claimed is:

An awning top for a boat comprising a pair of uprights for disposal in the fore and aft parts of the boat, members vertically slidable on the uprights, laterally extending 90 arms pivotally connected to the slidable members, said uprights being provided with a vertical series of openings, spring pressed bolts carried by the slidable members for interchangeable engagement with the said 95 openings, a longitudinal pipe pivotally connected to and extending between the slidable members, said pipe being provided adjacent its center with outlet openings, operating rods within the said pipe and connected to 100

the said bolts, and finger pieces carried by the outer ends of the operating rods and extending through said outlet openings for withdrawing the bolts from the said openings to permit the slidable members to be moved vertically on the uprights.

In testimony whereof, I affix my signature, in the presence of two witnesses.

NEWTON E. WILLIAMS.
